TELEPHONE SET

Henry Dreyfuss, South Pasadena, Calif., and Donald M. Genaro, Haworth, N.J., assignors to Bell Telephone Laboratories, Incorporated, Murray Hill, N.J., a corporation of New York

Original design application Feb. 2, 1968, Ser. No. 10,421, now patent No. 215,664, dated Oct. 21, 1969. Divided and this application Oct. 17, 1968, Ser. No. 18,393

Term of patent 14 years

Int. Cl. D14—03

U.S. Cl. D26—14

FIG. 1

FIG. 2

FIG. 3

FIG. 4

FIG. 1 is a perspective view of a telephone set showing our new design;

FIG. 2 is a perspective view as seen from the opposite side of FIG. 1;

FIG. 3 is a perspective view of a second modified embodiment of the telephone illustrated in FIG. 1; and

FIG. 4 is a perspective view of a third embodiment of the telephone illustrated in FIG. 1.

The broken line portions are shown for illustrative purposes only and do not form part of the design.

This is a division of design application Ser. No. D.10,421 filed Feb. 2, 1968 and now design patent Ser. No. D.215,664, filed Oct. 21, 1969.

We claim:

The ornamental design for a telephone set, substantially as shown and described.
